CLOTHES DRIER

Thomas S. Watson, Milwaukee, Wis., assignor of
one-half to Huebsch Manufacturing Company,
Milwaukee, Wis., a corporation of Wisconsin

Application December 11, 1940, Serial No. 369,553

11 Claims. (Cl. 68—242)

The invention relates to clothes driers and more particularly to a drier of the hydraulic pressure extractor type.

One of the main objects of the invention is to provide a drier of the type above described with improved means for locking the cover which will resist the heavy pressures to which it is subjected in practice and yet may be readily released without danger of jamming. More particularly, in the present invention the cover is firmly locked to the body of the container by a plurality of latches, and these latches are controlled by a reciprocating member carried and movable relative to said cover and also in the preferred form acting as a supplemental cover to deflect water expressed from the clothes into a drain passage.

A further object is to provide an arrangement of the type in which one cover will serve for a plurality of bags wherein the pressure fluid which may be moved to an operating position for each one of the bags but which is prevented from being moved to an operating position except with that unit in which the cover is positioned over the bag.

The invention further consists in the several features hereinafter set forth and more particularly defined by claims at the conclusion hereof.

In the drawings:

Fig. 1 is a vertical sectional view of a clothes drier embodying the invention, the section being taken on the line 1—1 of Fig. 2;

Fig. 2 is a plan view of the drier apparatus, parts being broken away and parts being shown in section;

Fig. 3 is a view of parts shown in Fig. 1 with the cover in raised position;

Fig. 4 is a vertical sectional view taken on the line 4—4 of Fig. 1;

Fig. 5 is a detailed sectional view taken on the line 5—5 of Fig. 4;

Fig. 6 is a detailed sectional view taken along the line 6—6 of Fig. 5.

Referring to the drawings, the numeral 8 designates, in each instance, a metal walled container having a grooved rim 9 at its top and an opening 10 in its bottom connected by a pipe 11 with a source of hydraulic fluid. The container is cylindrical with a conically curved bottom for strength, and preferably the depth of this casing or container should not exceed its diameter.

A bag 12 of flexible material fits within the container, and its rim 13 is adapted to fit in the groove of the rim 9 and a mating groove 14

formed in a clamping ring 15 secured to the rim 9 by a plurality of screws 16.

A cover 17 is adapted to fit over the top of either container 8 and has its rim 18 abutting the ring 15 and locked thereto by locking mechanism hereinafter described. The cover is provided with a plurality of apertures 19 uniformly distributed over its top to allow water or waste liquid to pass freely from the upper portion of the container.

The containers 8 are bound together by a frame plate 20 welded thereto and to which legs 21 are secured acting to support said containers in an elevated position and adjacent each other, so that the cover 17 may be used with one or the other container. Each container has an annular member 22 welded thereto and cooperating with the upper wall of the container proper to form a trough 23 to collect waste liquid draining off from the apertures 19 in the cover 17, each trough having a drain conduit 24 leading therefrom.

Each of the pipes 11 connect with a common valve housing 25 of a disc type so-called four-way rotary valve having three positions; to wit, a completely closed position, an "on" position for one of the containers while draining the other, and an "on" position for the other container while draining off the first container, this valve being of well known construction and, therefore, not shown in detail, said valve having a stem 26 to which the forked end 27 of a crank arm 28 is clamped by a screw 29. The hydraulic fluid from a suitable source of pressure supply is carried to the valve by a pipe 30, and the waste liquid is released through the pipe 31 connected to the housing 25.

The cover structure is quite heavy, and in order that it may be easily lifted and swung from side to side over one container or the other it is counterweighted and hung from a davit-type standard 32 whose lower end has an end thrust bearing 33 in a foot 34 carried by the frame members 35 and a lateral thrust bearing 36 mounted in a bearing housing 37 on the frame 20. A hollow counterweight 38 surrounds the upper straight portion of the standard 32 and is connected by metal straps 39 to a yoke 40 slidably mounted on said standard and to the end of a looped cable 41, whose runs pass over guide sheaves 42 and 43 on each side of the standard whereby the cable hangs down from the top of the standard or derrick mast 32 as a loop in which a pulley 44 is mounted, said pulley being connected with the cover 17 by a post 45 anchored to the cover and having the pulley block member 46 secured to

its upper end. The counterweight 38 is suspended by the cable 41, so that it is free to move up and down relative to the standard 32. The actual raising and lowering of the cover is accomplished by the operator through a lever 47 pivoted to the standard at one end 48 and having a handle 49 projecting out to a position in front of the two containers 8, this lever being connected to the cover through locking control mechanism hereinafter described.

For locking the cover 17 in operative position over the top of either container I provide a plurality of one piece latches 50 which are notched to provide jaws engaging over the cover rim 18 and the casing rim 9 in the closed position of the cover to lock these parts together, said latches being pivotally mounted at 51 on pin carrying bosses 52 secured to or formed integral with the rim 18 of the cover. The latches 50 being pivotally supported at their upper ends are free to swing to a locking position under the action of gravity when the cover is in its closed position. Means are provided for holding said latches in a locked position and also for moving said latches to an unlocked position. This means includes a locking ring 53 carried at the lower flanged edge of a supplemental cover or splash deflector 54 which is provided with a tubular hub 55 slidably mounted and guided on the post 45. Each latch 50 has a flat surface 56 with which the ring 53 engages in its locking position and surfaces 57 and 58 tapering from said surface 56 towards the ends of the latch with the upper end provided with a laterally extending projection 59 engaged by the ring 53 on its upward movement to swing the latches 50 outwardly to a cover release position. The tapered surface 58 of any latch if it fails to swing inwardly may be engaged by the ring 53 to urge it to a cover holding position. Thus a downward movement of the ring 53 acts to move and hold the latches 50 in cover-locking position, and an upward movement thereof acts to release and hold said latches in a release position.

Control of the movement of the locking ring 53 is through a manually operable lever 60 which is operatively connected with the hub 55 of the part 54 by a link connection which includes the lever 47. More particularly, the lever 47 has a pin and slot connection 61 with the sleeve or hub 55 and between this connection and the pivot pin 48, the lower end of the lever 60 is pivotally connected by a pin 62. Intermediate its ends the lever 60 has a pin and slot connection 63 with the pulley block 46. Actually the levers 47 and 60 are shown as having spaced sides to straddle certain of the parts. The above described arrangement permits the lever 60 to be moved relative to the cover 17 and its support including the post 45 so as to lock or unlock the latches 50 by the movement of the sleeve 55 through a slight swinging movement of the lever 47 relative to the post 45. In the release position of the ring 53 the lever 60 has been swung down so that it may be connected to move as a unit with the lever 47, in the raising or lowering of the entire cover structure, by means of a latch 64 pivotally mounted intermediate its ends on a pin 65 on the lever 47 and engageable with projections 66 on the lever 60. This latch is normally urged by a spring 67 to a position in which it will hook over the projections 66 when the levers 47 and 60 are moved together, said spring being operatively connected to the lower end of the latch 64 by a rod 68 slidably mounted in guides 69 on the han-

dle and having a bent outer end 70 for manual engagement to permit ready release of the latch 64 from the projections 66. The slots for the pin and slot connections 61 and 63 allow a certain amount of lost motion of the levers 47 and 60 relative to the cover support.

With the levers 47 and 60 in the position shown in Fig. 1 the locking ring 53 has been lowered to latch locking position, and under these conditions 10 hydraulic fluid may be introduced through its pipe 10 into the space between the container 8 and the bag 9, thus forcing the bag 12 previously charged with wet clothes upwardly toward the cover, so that the water in the clothes will be 15 squeezed out of them and flow through the openings 19 into the space between the top of the cover 17 and the splash cover part 54 and from thence downwardly into the trough 23. After this water extracting operation is finished and the water has 20 been released or allowed to drain from the space between the bag 12 and the container 8, the operator pulls the lever 60 down into latched engagement with the lever 47. During this downward movement of the lever 60 there is a slight 25 upward swinging movement of the lever 47 which causes the supplemental cover with its locking ring 53 to move upwardly, first free of the latch surfaces 56 and later engaging the projections to move the latches 50 to a release position, and 30 by this time the sleeve 55 is in a position to engage the lower end of the pulley bushing 46 on the post 45, so that thereafter when both levers 47 and 60 move together, the operator through the upward swinging movement of the lever 47 will raise the cover 17 clear of the top 35 of one of the containers 8, so that by swinging the lever 47 in a horizontal plane the standard 32 may be rotated to bring the cover into position over the other container 8 whose bag structure has been charged during the time the charge 40 in the first container was undergoing its extracting operation, and the lever 47 is then swung downwardly to a cover closing position, and then on the release of the latch 64 the lever 60 is permitted 45 to move to the upper full line position shown in Fig. 1 and the ring 53 consequently moved down to a latch locking position to permit the extracting operation to be carried out in this second container. Thus the same cover 50 and its locking and control mechanism can be used for a plurality of containers without interfering with the operation of either since the uncovered container is being either emptied and charged while the extraction operation is going 55 on in the covered container, but if with two containers and one cover mechanism the operator should accidentally turn on the hydraulic pressure fluid to the uncovered container, it might cause the bag to be emptied of its charge and 60 also injury to the bag which is an expensive item in the equipment. In order to prevent such a thing happening, means have been provided acting automatically or incidentally to the operation of the cover to prevent opening of the pressure supply to that container which is uncovered. 65 This means includes a valve lever lock for each container to prevent movement of the valve 25 to an "on" position, and which lock is released or rendered ineffective by the bringing of the cover to a locked position over the charged container. The valve lever locking means includes in each instance a blocking lever 71 pivotally mounted intermediate its ends on the valve housing 25 and connected by a pin and slot connection 72 with an arm 73 vertically adjustably 75

mounted on a vertically reciprocating rod 74 which is guided in a tubular guide 75 and is normally urged upwardly to a valve lever blocking position by a spring 76 interposed between the upper end of said guide and a shoulder on said rod, the upward movement of said rod being limited by the engagement of a stop shoulder 77 on the rod with the lower end of the guide 75. With the rod 74 in its upper position the lever 71 is in the dotted line position shown in Fig. 5 which brings its outer end into the path of a projection 78 on the valve turning lever 28, so that the valve cannot be turned in the direction of the lowered lever 71 until that lever is raised out of the way, and this raising of the lever takes place automatically through the action of the movement of the cover to a locked position since the cover, more particularly the latch control cover 54, has a pair of spaced lugs 79 on its outer part preferably at the back, one of these lugs engageable with the rod 74 for one container and the other with the other. Thus in an apparatus using two containers and one cover the operator can only operate the hydraulic pressure controlling valve in such a sequence as not to cause damage to the uncovered container.

The various parts of the cover and the container are made of metal best suited for the service which they have to stand.

I desire it to be understood that this invention is not to be limited to any particular form or arrangement of parts except in so far as such limitations are included in the claims.

What I claim as my invention is:

1. In a device of the class described, the combination of a container having an open end and a trough at said open end, a flexible bag clamped at its open end to the open end of said container and extending within the same, means for admitting pressure fluid between said container and bag, a removable apertured cover for said container, locking means carried by the cover for securing said cover to said container, and control means for said locking means movable relative to said cover and including a part acting as a supplementary cover to direct the overflow of fluid from said apertured cover into said trough.

2. In an apparatus of the character described, the combination of a plurality of like containers having open ends and arranged in spaced relation, a flexible bag clamped to the open end of each container and extending within the same, means for admitting pressure fluid between each container and its bag including a common supply and drain pipe and a valve controlling the passage of fluid to either container respectively, a removable cover for all of said containers, means carried by the cover for locking said cover to any one of said containers, and means controlled by the movement of the cover for preventing the operation of said valve to supply pressure fluid except only to the container then closed by said cover.

3. In a device of the class described, the combination of a container having an open end, a removable cover for said container, a plurality of latches pivotally mounted on said cover and movable to locking engagement with adjoining peripheral edges of said container and cover, a ring member movable substantially lengthwise of said latches to engage them to hold them in their locked position and move them to release position, and means for controlling said ring member.

4. In a device of the class described, the combination of a container having an open end, a removable cover for said container, a plurality of latches pivotally mounted on said cover and gravity actuated to locking engagement with adjoining peripheral edges of said container and cover, a ring member movable substantially lengthwise of said latches to a position to hold said latches in their position of locking engagement and also movable substantially lengthwise of said latches to engage with a part of said latches to positively release the same from locking engagement with said container, and means carried by the cover for controlling said ring member.

5. In a device of the class described, the combination of a container having an open end, a removable cover for said container, a plurality of latches pivotally mounted on said cover and normally biased to locking engagement with adjoining peripheral edges of said container and cover, and a ring member movable substantially lengthwise of said latches to a position to hold said latches in their position of locking engagement.

6. In an apparatus of the character described, the combination of a container having an open end, a removable cover for said container, a counterweighted extensible support for said cover, a plurality of latches pivotally mounted on said cover and normally biased to locking engagement with adjoining peripheral edges of said container and cover, a ring member movable to a position to hold said latches in their position of locking engagement and into a position to positively release said latches from their locked position, a lever for moving said extensible support to raise and lower said cover, and control means for said ring including a manually controlled lever carried by said support and operatively connected to said ring through said first named lever.

7. In an apparatus of the character described, the combination of a container having an open end, a removable cover for said container, locking means carried by the cover for securing said cover to said container, operator controlled means for controlling said locking means, means for suspending said cover in raised position above said container, a lever having a lost motion connection with said suspending means for raising said cover, and a lock release lever connected with said suspending means and said first named lever and operable through said first named lever to move the controlling means for said locking means to a lock release position.

8. In an apparatus of the character described, the combination of a container having an open end, a removable cover for said container, locking means carried by the cover for securing said cover to said container, operator controlled means for controlling said locking means, means for suspending said cover in raised position above said container, a lever having a lost motion operating connection with said suspending means for raising said cover, a lock release lever associated with said suspending means and said first named lever and operable to move the controlling means for said locking means to a lock release position, and means for locking said levers together when said locking means are released.

9. In an apparatus of the character described, the combination of a container having an open end, a removable cover for said container, a plurality of latches pivotally mounted on said cover

and normally biased to locking engagement with adjoining peripheral edges of said container and cover, a ring member movable to a position to hold said latches in their position of locking engagement and into a position to positively release said latches from their locked position, means for supporting said cover, a lever connected to said ring for moving said supporting means to raise said cover, and control means for said ring including a manually controlled lever carried by said supporting means and operatively connected to said ring through said first named lever.

10. The combination with a pair of receptacles and a cover common to both receptacles, of means for shifting said cover from one receptacle to the other comprising a rotatable standard disposed in a plane between the receptacles, a counterweight carried by said standard, a cable

operably connecting said counterweight with said cover, and a lever fulcrumed on said standard and operably connected with the cover for raising the cover and turning the standard.

11. In an apparatus of the character described, the combination of a container having an open end, a removable cover for said container, locking means carried by the cover for securing said cover to said container, a rotatable standard, manually controlled means for raising and lowering said cover including means for suspending the cover from said standard and including a cover counterweight, operator controlled means for controlling said locking means, the means for raising and lowering said cover including a lever having a lost motion connection with said cover and forming a part of the control for said locking means.

THOMAS S. WATSON.
